UNITED STATES PATENT OFFICE.

JULIUS G. ZWICKER, OF BERKELEY, CALIFORNIA.

CONCRETE-PIPE MACHINE.

1,418,859.

Specification of Letters Patent. Patented June 6, 1922.

Application filed April 12, 1920. Serial No. 373,160.

To all whom it may concern:

Be it known that I, JULIUS G. ZWICKER, a citizen of the United States, residing at Berkeley, in the county of Alameda and State of California, have invented certain new and useful Improvements in Concrete-Pipe Machines, of which the following is a specification.

My invention relates to an apparatus for molding pipe sections, and is particularly adapted for the use of concrete as the molded material, and for the production of such sections with interfitting threaded ends, in this respect being similar in purpose to the concrete-pipe machine for which United States Letters Patent No. 1,275,353 was issued to me on August 13, 1918, to which reference may be made if desired.

Broadly, the objects of my present invention are similar to those set forth in the specification of said patent, viz:—to provide a molding apparatus by means of which a wet or poured concrete mixture may be artificially and rapidly set by the forcible expression of the greater portion of the water contained in the mixture, to enable its immediate removal from the mold; and further to provide, in such an apparatus, a mold of absolute accuracy, so that every article molded therein will be identical with every other article. The advantages gained by the attainment of these objects are fully expounded in the specification of said patent, and are now clearly recognized in the art, so that they need not be entered into here.

As in the machine described in said patent, I now make use, in the present apparatus, of separate ring molds for forming the threads upon the ends of the pipe section. Moreover, in the present apparatus, I compress the pipe section in a manner broadly similar to that employed in said prior machine, namely by pressure applied in a direction at right angles to the longitudinal axis of the molds, that is, to the side of the section to be molded.

More specifically, the objects of my present invention are to provide a machine for the described purpose in which the interior surface of the molded pipe section can be given a smooth finish, similar to that obtained by the well-known process of hand trowelling concrete surfaces, so that said interior surface, when dry, is smooth, hard, and impervious; and further to provide a machine capable of making concrete pipe

sections in the least possible time. For the attainment of this latter object, I employ power means for performing all the major operations of the process, so that said operations are accomplished swiftly and accurately without exertion on the part of the operator. In fact, by continuous operation of the machine hereinafter described, I am able to make one pipe section every minute.

A still further object of my invention is to provide means for adjustment of the machine so that pipe sections of various diameters and thickness, within certain limits, can be made in one machine, and so that the degree of compression can be properly correlated to the amount of concrete in the mold, regardless of the size or thickness of the pipe formed.

Although my invention is herewith described and illustrated as a machine for making concrete pipe sections, it is to be understood that other materials capable of being molded under pressure may be used, and by making minor alterations in the form and construction of the machine, articles other than pipe sections may be formed.

With this in view, my invention will now be described in detail with reference to the accompanying sheets of drawings, where-in:

Fig. 1 is a side elevation of my complete machine.

Fig. 2 is a vertical section, enlarged, of the upper portion of the machine, showing the molds and associated mechanism.

Fig. 3 is a horizontal section in two planes, taken approximately on the lines *a—a* and *b—b* of Fig. 2 and viewed in the direction of the arrows.

Fig. 4 is a vertical sectional detail, enlarged, showing portions of the upper ends of the molds, the upper thread mold, and associated mechanism.

Fig. 5 is a vertical sectional detail, enlarged, of the feed hopper.

Fig. 6 is a central vertical section, enlarged, of the lifting mechanism located in the base of the machine.

Fig. 7 is a top plan view, greatly enlarged, of one each of the inner and outer cylindrical mold segments.

In the drawings, the reference numeral 1 designates the upright columns of a supporting frame. There are preferably four such columns, springing from a base 2, Fig. 1, set upon a suitable floor or foundation, the

level of which is represented by the line 3—3. The upper portions of said columns 1 supports two spaced horizontal circular channels or guides 4, Figs. 1, 2 and 3. Vertical spacer members 5 between said guides 4, serve to hold the same in proper mutual relation.

The circular channels 4, each of which is formed of an upper and a lower plate secured together as by bolts 6, Figs. 2 and 3, have a series of radially disposed inwardly directed guide-ways 7, Figs. 2, 3 and 5, preferably square in cross-section. Within said guide-ways are slidable plungers 8, each of which carries, at its outer end, a roller 9, positioned to bear against the flat surface of a cam block 10, Figs. 2 and 3. Each of said blocks 10 is secured to the inner periphery of a corresponding ring 11 mounted for oscillatory motion in its corresponding circular guide 4, so that, by the oscillation of said rings 11 the plungers 8 are moved in, or are allowed to be moved out by springs 12, Fig. 3, inserted between 25 shoulders 13 on said plungers and the inner faces of the channels 4.

On the inner ends of the plungers 8 are formed dowels 14, Fig. 2, which fit snugly into sockets in vertically disposed bars 15, Figs. 2 and 3. Each of said bars 15 is thus carried by a pair of vertically aligned plungers 8, one in the upper series and one in the lower, and the entire set of said bars, which are positioned close together, forms 35 a cylindrical vertically disposed cage constituting the outer mold for a section of pipe.

The inner surfaces of the vertical bars or mold segments 15 are formed into a grid 40 by a series of parallel vertically disposed segmental ribs or tongues 16, Fig. 7, whose inner faces are formed upon the arc of a circle, and which are separated, at said inner faces, by very narrow slits 17 leading 45 into enlarged vertical passages 18 between the segmental tongues. The entire surface of the cylinder formed by the bars 15, therefore, comprises a series of closely spaced parallel segments separated by very narrow 50 slits. As the bars 15 are moved in or out by their respective plungers 8 and springs 12, the diameter of the cylinder formed by said bars is, of course, decreased or increased, and the spaces between adjacent bars are 55 sufficient to permit such contraction and expansion, but in practice, in a machine where the diameter of the cylinder is about eight inches, and which is built up of sixteen bars, as in the machine herewith illustrated, the 60 maximum distance between adjacent bars 15 need not be greater than three sixty-fourths of an inch; and in a machine of this size I prefer to make the slits 17 between adjacent segments 16 of the grid about one sixty-fourth of an inch.

Rotation of the cam rings 11, to cause contraction or expansion of the cylindrical mold, is effected by means of a pair of oppositely positioned hydraulic cylinders 19, Fig. 1, set in pivotal supports 20 for horizontal swinging movement. Each of said cylinders 19 has within it a piston 21, Fig. 3, from which extends a piston rod 22, passing through a suitable packing gland 23 and a guide 24, and pivotally connected at its outer end with a lever 25 fulcrumed, at 70 26, at its middle. The outer end of each lever 25 is connected by a link 27 with a vertical rod 28, Figs. 1 and 3, extending between and connecting the upper and lower rings 11. 80

Adjustable stops 29 are provided on each piston rod 22 to limit its motion by contacting with the guide 24, and a lineal adjustment 29' is provided for varying the effective length of the piston rod 22. 85

Rising from the upper circular guide 4 is a yoke frame 30, Figs. 1 and 2, which has a cross member 31 in which is formed a central hub 32, in axial alignment with the center of the cylindrical mold described 90 above. To the lower end of said hub is secured a plate or head 33, Figs. 2 and 4, whose outer edge rests upon a cylindrical cap 34, Figs. 1, 2 and 4. The lower end of said cap is flanged, and rests upon a separate conical flange 35, which, in turn, rests upon and is secured to the upper circular guide 4, the members 33, 34 and 35 thus forming an end closure or cap for the cylindrical mold. 100

The hub 32 supports and provides a bearing for a rotatable tube 36, Figs. 2 and 3, which extends centrally through the outer mold. In the upper end of said tube is fixed a bevel gear 37, Figs. 1 and 2, which 105 meshes with a corresponding bevel gear 38 fixed upon the inner end of a horizontal shaft 39 carried in a suitable journal 40 and having a pulley 41 fixed upon its outer end, by means of which it and the tube 36 may 110 be rotated.

Within the tube 36 is an axially slideable rod 42, Figs. 1 and 2, which projects through the gear 37 at its upper end and is formed with an annular groove 43, in which rides 115 the forked end of a lever 44, fulcrumed at 45, by means of which said rod 42 may be moved vertically. Said rod 42 carries a series of transversely disposed pins 46, Fig. 2, which extend, through vertically directed 120 slots 47 in the tube 36, into conical wedge blocks 48, Figs. 2 and 3, surrounding said tube and slidably mounted thereon.

The mold for the inner surface of the pipe section comprises a series of adjacent vertical bars 49, Figs. 2, 3 and 7, forming a cylinder positioned concentrically within the outer mold. Said bars 49 rest upon a bottom end plate 50, Fig. 2, and a similar end plate 51 is provided at the top, both end 130

plates being carried by the tube 36. Guide members 52 are also carried by the tube 36 immediately within the end plates 50 and 51, said guide members being formed with 5 radial slots or guide ways 53, Fig. 4, adapted to receive lugs 54 projecting inwardly from the end portions of the bars 49. Springs 55, associated at top and bottom with each of said bars 49, act to draw 10 the same in toward the center.

The bars 49 are formed upon their backs with inwardly projecting lugs 56, Figs. 2 and 3, having inclined faces adapted to bear against the conical wedge blocks 48, so that 15 by the elevation of the central rod 42, carrying with it the blocks 48, the bars 49 are forced outwardly, and the cylinder forming the inner mold or core is made larger in diameter; and conversely, upon the lower- 20 ing of the rod 42, said bars are drawn inwardly, by their springs 55, to make said mold smaller.

The outer surfaces of the bars 49 are formed into grids, as in the case of the outer 25 mold bars 15, by a series of vertical segmental ribs 57, Fig. 7, whose outer surfaces are formed upon the arc of a circle, and which are separated, at said outer surfaces, by narrow slits 58 leading into larger vertical 30 cal passages 58'. The spaces between adjacent segmental ribs 57 and between adjacent bars 49 are approximately the same as those in the outer mold construction previously described. The entire inner mold structure 35 or core, being carried by the tube 36, is rotatable by means of power applied to the pulley 41.

Surrounding the upper end portion of the core and lying within the cylindrical shell 40 34, is a ring 59, Figs. 2 and 4, suspended by 45 slideable rods 60 from a yoke 61, Figs. 1 and 2, said rods passing through guides 62, Fig. 4, in the head plate 33, which is flanged, as shown in Figs. 2 and 4, to permit the ring 59 to be drawn up clear of both the outer and the inner molds. The yoke 61, Fig. 2, is supported by a vertical piston rod 63 which passes through a hydraulic cylinder 64 carried by the frame 30, and is connected 50 with a piston 65 within said cylinder. Suitable packing glands 66 are provided where the rod 63 passes through the heads of said cylinder, and the upper end of said rod passes through a guide 67 and is provided 55 with adjustable stops 68 contacting with said guide to limit the motion of said rod.

The ring 59 carries a series of depending spring fingers 69, Figs. 2 and 4, each having on its back a lug 70, Fig. 4, adapted to 60 engage a shoulder 71 formed on the inner surface of the cylindrical member 34, so that when the ring 59 is raised from the position shown, the fingers 69 are forced inwardly by the contact of their lugs 70 with said 65 shoulder. The lower ends 72, of said fingers

69 are bent inwardly and pointed, to engage and grip the upper thread mold 73. This thread mold, which is shown in Figs. 1, 2, 4 and 5, is for the purpose of forming the male thread upon the upper end of the pipe 70 section, and as such is provided with an inner flange 74, Fig. 4, of such size that it will fit closely about the core when the latter is fully expanded, and an outer flange 75 of the same diameter as the outside of the 75 finished pipe and fitting easily within the cylindrical member 34. Between said flanges are formed interior threads 76. The thread mold is preferably formed of soft metal, and as a result is readily engaged by the pointed 80 ends 72 of the spring fingers 69.

The lower thread mold 77, Figs. 1 and 2, which is substantially similar to the upper thread mold 73, except that it is formed with exterior threads for molding female threads 85 upon the lower end of the pipe section, is initially mounted upon an annular truck 78, Fig. 1, said truck having wheels 79 adapted to run upon the rails 80 of a suitable track laid between the columns 1 in the lower portion 90 of the machine.

The placing of said lower thread mold upon the truck 78 is the first step in the operation of the machine to make a section of pipe. A reinforcing coil 81, Fig. 1, is 95 then placed, in an upright position, upon said lower thread mold, and the upper thread mold 73 is placed upon the upper end of said coil. The reinforcing coil 81 may be of any suitable construction, but in practice 100 I prefer to use the reinforcing coil for concrete pipes for which United States Letters Patent No. 1267835 was issued to me on May 28, 1918. The truck 78, with the thread molds and the reinforcing coil thereon, is 105 then run into the lower part of the machine, and placed below and in vertical alignment with the inner and outer cylindrical molds described above, as shown in Fig. 1.

In this position, the lower thread mold 77 110 is in vertical alignment above a lifting table 82, Figs. 1 and 6, carried upon the upper end of a vertically movable rod 83, Fig. 6, whose lower end carries a piston 84 operable within a hydraulic cylinder 85. Suitable 115 fluid connections 86 and 87 are provided for operating said piston, and a packing gland 88 surrounds the rod 83 where it passes out of the upper end of the cylinder 85. A stop 89 is also provided at the upper end of said 120 cylinder upon which the lifting table 82 seats when in its lowermost position, as shown in Figs. 1 and 6.

The truck 78 having been positioned above the lifting table 82, said table is raised, by 125 means of its hydraulic cylinder, and, passing upward through the truck 78 engages and lifts the lower thread mold 77 with the reinforcing coil 81 and the upper thread mold 73 superposed thereon, and positions 130

the same within the annular space between the inner and outer cylindrical molds, as shown in Fig. 2, said inner and outer cylindrical molds having been previously contracted and expanded, respectively, to the limits of their movement.

The parts now occupy the relative positions shown in Fig. 2. A central dowel 90 on the lifting table 82 has entered a socket 91 in the lower end of the central tube 36, thereby centering said lifting table. The inner cylindrical mold is then expanded, by means of the lever 44, to its limit, which corresponds to the inside diameter of the finished pipe section. Next the ring 59 is raised, by means of fluid admitted to its hydraulic cylinder 64 below the piston 65, and the spring fingers 69, gripping the upper thread mold 73, cause the same to be lifted, 20 along with the ring 59, to the position shown in section in Fig. 5.

On one side of the cylindrical cap member 34 is a feed hopper 92, Fig. 5, whose lower portion communicates with the annular space between the inner and outer cylindrical molds by means of an opening 93. A segmental sliding gate 94 is provided for closing said feed opening, and said gate is operated by a horizontally disposed hydraulic cylinder 95 having a piston 96 and a piston rod 97 connected directly with said gate.

The upper thread mold 73, as shown in Fig. 5, has been raised above said feed opening 93. The machine is now ready for pouring. Wet concrete mixture is introduced through the feed hopper 92 to fill the annular space between the inner and outer cylindrical molds, surrounding and embedding within itself the reinforcing coil 81. The gate 94 is then closed by the action of its hydraulic cylinder 95, and the upper thread mold is forced downward, against the wet concrete, by the hydraulic cylinder 64, Fig. 2, to the limit of its motion, at which point 45 said thread mold is freed from the spring fingers 69 by the passage of the lugs 70 below the shoulder 71, Fig. 4. The outer cylindrical mold is then contracted, by means of the hydraulic cylinders 19, Figs. 1 and 3, and the associated mechanism described above, to squeeze the water out of the concrete mixture, said water escaping through the slits 17 and 58, Fig. 7, in the outer and inner mold surfaces respectively, and running down through the passages 18 and 58'.

In this connection it should be noted that, on account of the shape of the cam surfaces 10, Fig. 3, carried by the oscillatory rings 11, the maximum pressure is exerted upon the outer cylindrical mold at the end of its contracting movement. As the concrete mixture loses its water and becomes more dense, the contracting movement of the outer mold becomes slower and its power increases. The

stops 29 and the connections 29' of the hydraulic cylinders 19 are so adjusted that the pistons 21 come to the end of their travel just as the apices of the cams 10 are reached, and the length of travel of said pistons is just sufficient to cause the proper amount of contraction of the outer mold to dry the amount of concrete used in the formation of the pipe section. To make a pipe section having walls of greater or less thickness, the outer mold segments 15 can be replaced by others of different thickness, and in this case the amount of contraction of said outer mold must be adjusted, by means of the stops 29 and the connections 29', to be proportionate to the amount of concrete used. In case it is desired to make a pipe section of different inside diameter, the entire inner cylindrical mold or core can be replaced with one of the proper size, and this also would necessitate an adjustment of the amount of contraction of the outer mold.

Going back to the description of the operation of the machine, after the concrete has been compressed, the inner cylindrical mold or core is contracted by raising the lever 44, Figs. 1 and 2, and set to rotating by power applied through the pulley 41. The operator then, by careful manipulation of the lever 44, expands the core gently until its segments just touch the inner surface of the pipe section, and by this light rubbing, said inner surface is smoothed. In fact, by skillful manipulation of the hand lever 44, an effect can be produced which closely resembles that of hand-trowelling, so that a smooth inner surface is formed, rich in cement, which when dry, renders the pipe section practically impervious, even at high pressures.

The smoothing operation completed, the core is contracted and stopped; the outer cylindrical mold is expanded to free the pipe section; and the lifting table 82, Fig. 2, is let down, to lower the finished pipe section on to the truck 78, Fig. 1, upon which it is carried out of the machine. The thread molds are allowed to remain on the pipe section until the concrete has hardened, when they can be easily removed. It is also desirable to leave the pipe section on the truck 78 until the concrete hardens to avoid possible injury.

It is necessary to wash the cylindrical molds at frequent intervals to prevent the accumulation and setting of particles of concrete. This need not be done after every cycle of operation, as the particles of concrete adhering to the slits and passages of the mold segments will not set for several minutes, but in order to accomplish this washing with the least possible delay, I provide the following devices. The cylindrical cap member 34 is formed with an annular

chamber 98, Fig. 4, which has a water inlet connection 99 and an annular opening 100 positioned immediately above the drain passages 18, Fig. 7, of the outer mold sections, 5 so that water, introduced through said inlet connection 99, flows downward through said drain passages 18, washing the same. A similar annular chamber 101, Fig. 4, is formed in the cap member 33, having a 10 water inlet connection 102 and an annular opening 103 through which water can be fed into the drain passages 58', Fig. 7, of the core segments. The surfaces of both inner and outer mold segments are flushed by 15 water introduced through a connection 104, Fig. 4, into the annular space between the cap member 33 and the cylindrical member 34, and passing on both sides of an annular spreader 104' and the ring 59. All of this 20 flushing water runs out the bottom of the cylindrical molds and is caught in a basin 105, Fig. 6, formed in the base 2, from which a suitable drain 106 is provided.

In order to make possible the shipping 25 or transportation of the machine, without the employment of heavy and costly derricks and other apparatus, I provide means for lowering the entire mechanism upon its supporting columns 1. For this purpose the 30 ring guides 4 are secured to said columns by split ears 107, Figs. 1 and 3, which are normally clamped about said columns by bolts 108. The columns 1 are threaded, as shown in Fig. 1, and upon each is fitted an internally threaded nut 109, the four nuts 109 being adapted to support the weight of the entire super-structure when the clamp-bolts 108 are loosened.

The nuts 109 have secured to them sprockets 110, Fig. 3 and these sprockets are interconnected by means of a chain 111, Figs. 1 and 3, so that all four nuts are rotated together. One of the nuts is provided with ratchet teeth 112 adapted to be engaged by 45 either one of two oppositely operating pawls 113 carried by an oscillatory lever 114.

Therefore, by operating the lever 114, the four nuts 109 are rotated, and the entire mechanism can be raised or lowered, depending upon the position of the pawls 113, the ears 107 sliding freely upon the columns 1 after the bolts 108 are loosened. When the super-structure is lowered between the columns 1, the machine can be handled more 55 easily, without fear of damage, and occupies less space in shipment, and, carrying its own lifting mechanism, can be set up quickly and easily without the aid of a derrick.

The mechanism thus described is also of 60 great assistance in dis-assembling the machine for repair. In this case the upper ring guide 4, Fig. 2, can be clamped upon the columns 1 and the lower one loosened. Then by removing the bolts 6, and lowering the

nuts 109, either the lower or the upper ring 65 guides, or both, can be taken apart, to give access to the radial cam followers.

I claim:

1. A concrete-pipe machine comprising a rotatable inner mold capable of contraction 70 to free the molded pipe; an outer mold capable of contraction to compress the concrete and of expansion to free the molded pipe; means for contracting and expanding said molds; and means for rotating said inner 75 mold.

2. A concrete-pipe machine comprising a rotatable inner mold capable of contraction and expansion; an outer mold capable of contraction to compress the concrete; means 80 for contracting said outer mold; means for rotating said inner mold; and means for contracting and expanding said inner mold during the rotation thereof.

3. A concrete-pipe machine comprising a 85 rotatable inner mold capable of contraction and expansion; a non-rotatable outer mold; means for rotating said inner mold; and means for contracting and expanding said inner mold during the rotation thereof. 90

4. A concrete-pipe machine comprising an inner mold; an outer mold capable of contraction to compress the concrete, said outer mold being formed of a plurality of radially movable segments; a cam follower secured to the back of each mold segment; an angularly movable ring encircling said segments; a plurality of cams carried by said ring for engagement with said cam followers, the inclination of said cams decreasing from their bases to their apices, whereby upon partial rotation of said ring, said segments are caused to move inwardly with gradually decreasing speed and increasing force; and means for causing partial rotation of said ring. 105

5. A concrete-pipe machine comprising an inner mold; an outer mold capable of contraction to compress the concrete, said outer mold being formed of a plurality of radially movable segments; a cam follower secured to the back of each mold segment; an angularly movable ring encircling said segments; a plurality of cams carried by said ring for engagement with said cam followers, said 110 cams being formed as chords of the circle of said ring; and means for causing partial rotation of said ring to move said mold segments inwardly. 115

6. A concrete-pipe machine comprising an 120 inner mold; an outer mold capable of contraction to compress the concrete, said outer mold being formed of a plurality of radially movable segments; a cam follower secured to the back of each mold segment; an angularly movable ring encircling said segments; a plurality of cams carried upon the inner periphery of said ring for engagement with 125

said cam followers, each of said cams having a flat face formed as a chord of the circle of said ring; and means for causing partial rotation of said ring to move said mold 5 segments inwardly.

7. A concrete-pipe machine comprising an inner mold; an outer mold capable of contraction to compress the concrete, said outer mold being formed of a plurality of radially 10 movable segments; a cam follower secured to the back of each mold segment; an angularly movable ring encircling said segments; a plurality of cams carried by said ring for engagement with said cam followers; an hydraulic cylinder for actuating said ring; a piston within said cylinder; and a system of levers and links connecting said piston with said ring, whereby movement of said piston causes partial rotation of said 15 ring, to move said mold segments inwardly.

8. A concrete-pipe machine comprising an inner mold; an outer mold capable of contraction and expansion, said outer mold being formed of a plurality of radially 20 movable segments; a cam follower secured to the back of each mold segment; an oscillatory ring encircling said segments; a plurality of cams carried by said ring for engagement with said cam followers; a spring associated 25 with each segment for causing its follower to follow the corresponding cam of said ring; and mechanism for oscillating said ring to cause contraction and expansion of said outer mold.

9. A concrete-pipe machine comprising an inner mold capable of contraction to free the molded pipe; an outer mold capable of contraction and expansion, said outer mold being formed of a plurality of radially 30 movable segments; a cam follower secured to the back of each mold segment; an oscillatory ring encircling said segments; a plurality of cams carried by said ring for engagement with said cam followers; a spring 35 associated with each segment for causing its follower to follow the corresponding cam of said ring; and mechanism for oscillating said ring to cause contraction and expansion of said outer mold.

10. A concrete-pipe machine comprising an inner mold capable of contraction to free the molded pipe, said inner mold being formed of a plurality of radially movable 40 segments having lugs projecting from their inner surfaces; means for contracting said inner mold comprising a central longitudinally movable rod carrying wedge blocks adapted for engagement with the lugs of said inner mold segments; an outer mold 45 capable of contraction and expansion, said outer mold being formed of a plurality of radially movable segments; a cam follower secured to the back of each mold segment; an oscillatory ring encircling said segments;

a plurality of cams carried by said ring for 55 engagement with said cam followers; a spring associated with each segment for causing its follower to follow the corresponding cam of said ring; and mechanism for oscillating said ring to cause contraction 70 and expansion of said outer mold.

11. A concrete-pipe machine comprising a rotatable inner mold capable of contraction and expansion, said inner mold comprising a plurality of radially movable segments having 75 guide fingers and compression lugs projecting from their inner surfaces, a rotatable supporting tube having radially socketed members adapted to receive the guide fingers of the mold segments and having a longitudinally directed slot in the region of the compression lugs of said segments, an annular wedge ring slidably mounted on said tube and adapted for engagement with said compression lugs, a longitudinally movable rod within said tube and connected through the slot thereof with said wedge ring whereby movement of said rod causes the expansion of said mold, and springs associated with said segments for causing the 90 contraction of said mold; an outer mold capable of contraction and expansion; means for contracting said outer mold; and means for rotating said inner mold.

12. A concrete-pipe machine comprising inner and outer cylindrical molds each formed of a series of separate radially movable parallel segmental bars, the molding surface of each bar being made up of a plurality of parallel longitudinally disposed segments 100 separated by narrow slits leading into enlarged drain passages behind said surface.

13. A concrete-pipe machine comprising a rotatable inner mold capable of contraction to free the molded pipe and an outer mold 105 capable of contraction to compress the concrete and of expansion to free the molded pipe, the molding surfaces being formed of a plurality of parallel segments separated by narrow slits leading into enlarged drain 110 passages behind said surfaces; means for contracting and expanding said molds; and means for rotating said inner mold.

14. A concrete-pipe machine comprising a rotatable inner mold and an outer mold, 115 each capable of contraction and expansion, and each formed of a series of separate radially movable parallel segmental bars, the molding surface of each bar being made up of a plurality of segments separated by narrow slits leading into enlarged drain passages behind said surface; means for contracting and expanding said molds; and means for rotating said inner mold.

15. A concrete-pipe machine comprising 125 vertically disposed inner and outer molds capable of contraction and expansion, respectively to free the molded pipe; separate

end molds; and means for supporting the freed molded pipe and lowering the same out of the sphere of action of said inner and outer molds.

5 16. A concrete-pipe machine comprising vertically disposed inner and outer molds capable of contraction and expansion, respectively, to free the molded pipe; separate end molds; means for positioning said end 10 molds in operative relation to said inner and outer molds, and for supporting the freed molded pipe and lowering the same out of the sphere of action of said inner and outer molds.

15 17. A concrete-pipe machine comprising inner and outer molds capable of adjustment to free the molded pipe; separate end molds; means for removing the molded pipe, with said end molds positioned thereupon, 20 from the machine; and means for supporting the freed molded pipe and for lowering the same from said inner and outer molds to said removing means.

18. A concrete-pipe machine comprising 25 vertically disposed inner and outer molds capable of adjustment to free the molded pipe; separate end molds; means for removing the molded pipe, with said end molds positioned thereupon, from the machine; devices for 30 lowering the freed molded pipe from said inner and outer molds and placing the same upon said removing means; and a hydraulic cylinder for actuating said lowering devices.

19. In a machine for making reinforced 35 concrete pipe sections, each section having embedded therein a reinforcing coil; inner and outer molds capable of adjustment to free the molded pipe; separate end molds; and means for positioning said end molds 40 and the reinforcing coil between said inner and outer molds.

20. In a machine for making reinforced 45 concrete pipe sections, each section having embedded therein a reinforcing coil; inner and outer molds capable of adjustment to free the molded pipe; separate end molds; and means for positioning said end molds and the reinforcing coil between said inner and outer molds, and for supporting the 50 freed molded pipe and lowering the same from between said inner and outer molds.

21. In a machine for making reinforced 55 concrete pipe sections, each section having embedded therein a reinforcing coil; inner and outer molds capable of adjustment to free the molded pipe; separate end molds; carrier means supporting said end molds and the reinforcing coil and positioning the same below the inner and outer molds, and 60 for removing the molded pipe, with said end molds positioned thereon, from the machine; and elevating means for lifting the end molds and the reinforcing coil from said carrier means and positioning the same between

said inner and outer molds, and for lowering 65 the freed molded pipe from between said inner and outer molds on to said carrier means.

22. A concrete-pipe machine comprising vertically disposed inner and outer molds; 70 separate end molds; a feed hopper for the poured concrete having a feed aperture positioned above the outer mold; and means for temporarily engaging the upper end mold and raising the same above said feed 75 aperture and for forcibly lowering said upper end mold into its final position.

23. A concrete-pipe machine comprising vertically disposed inner and outer molds; 80 separate end molds; a feed hopper for the poured concrete having a feed aperture positioned above the outer mold; a gate for closing said aperture; means for forcibly closing said gate; and means for temporarily engaging the upper end mold and raising 85 the same above said aperture and for forcibly lowering said upper end mold into its final position.

24. A concrete-pipe machine comprising vertically disposed inner and outer molds; 90 separate end molds; a feed hopper for the poured concrete having a feed aperture positioned above the outer mold; means for positioning said end molds between said inner and outer molds and for removing the molded pipe, with said end molds positioned 95 thereon, from between said inner and outer molds; and means for raising the upper end mold above said feed aperture during the pouring operation, and for subsequently 100 forcibly lowering said upper end mold into its final position.

25. A concrete-pipe machine comprising a base; vertically disposed supporting columns rising therefrom; associated inner and outer 105 cylindrical molds carried by the upper portion of said columns, said molds being capable of adjustment to free the molded pipe; and means associated with said base for supporting and lowering the freed molded pipe 110 from its molding position between said inner and outer molds.

26. A concrete-pipe machine comprising a base; vertically disposed supporting columns rising therefrom; associated inner 115 and outer pipe molds carried by said columns; and means for raising and lowering both of said molds as a unit upon said columns.

27. A concrete-pipe machine comprising a 120 base; vertically disposed supporting columns rising therefrom; a frame adjustably mounted on said columns; associated inner and outer pipe molds carried by said frame; and means for raising and lowering said frame 125 upon said columns.

28. A concrete-pipe machine comprising a base; vertically disposed threaded support-

ing columns rising therefrom; a frame slidably mounted on said columns; associated pipe molds carried by said frame; and nuts mounted on said columns, in threaded engagement therewith, for supporting and adjusting said frame.

29. A concrete-pipe machine comprising a base; vertically disposed threaded supporting columns rising therefrom; a frame slidably mounted on said columns; associated pipe molds carried by said frame; interconnected nuts mounted on said columns, in threaded engagement therewith, for supporting said frame; and means for simultaneously operating all of said nuts to raise and lower said frame.

30. A concrete-pipe machine comprising a base; vertically disposed threaded support-

ing columns rising therefrom; a frame slidably mounted on said columns; associated pipe molds carried by said frame; nuts mounted on said columns, in threaded engagement therewith, for supporting said frame; sprockets fixed to said nuts; chains inter-connecting said sprockets, whereby all of said nuts are operated in unison; and means for operating said nuts to raise and lower said frame.

In testimony whereof I have signed my name to this specification in the presence of two subscribing witnesses.

JULIUS G. ZWICKER.
